DESIGN FOR A BALLOON CART

John J. Kelly, New York, N. Y.

Application June 27, 1938, Serial No. 78,101

Term of patent 14 years

To all whom it may concern:

Be it known, that I, John J. Kelly, a citizen of the United States, residing at No. 1. Christopher Street, in the county of New York, city and State of New York, have invented a new, original, and ornamental Design for a Balloon Cart, of which the following is a specification, reference being had to the accompanying drawing, forming part thereof.

Fig. 1 is a perspective view of a balloon cart showing my new design; and

Fig. 2 is a perspective view thereof taken from the opposite side of Fig. 1.

I claim:

The ornamental design for a balloon cart, as shown.

JOHN J. KELLY.
